Primary Examiner — Rosemary K Tarcza(74) *Attorney, Agent, or Firm* — Michael J. Giannetta; Barbara R. Doutre(57) **CLAIM**

The ornamental design for an battery pack for mobile terminal, as shown and described.

DESCRIPTION

FIG. 1 is a front perspective view of an ornamental design for battery pack for mobile terminal;

FIG. 2 is a rear perspective view thereof;

FIG. 3 is a front view thereof;

FIG. 4 is a rear view thereof;

FIG. 5 is a first side view thereof;

FIG. 6 is a second side view thereof;

FIG. 7 is a top view thereof; and,

FIG. 8 is a bottom view thereof.

The broken lines shown in FIGS. 1-8 are included for the purpose of illustrating environmental elements only and form no part of the claimed design.
